UNITED STATES PATENT OFFICE.

CLIFTON F. SAUNDERS, OF ANCON, CANAL ZONE.

MECHANICAL PHOTOGRAPH AND BLUE-PRINT DRIER.

1,301,750.

Specification of Letters Patent. Patented Apr. 22, 1919.

Application filed November 1, 1913. Serial No. 260,723.

To all whom it may concern:

Be it known that I, CLIFTON F. SAUNDERS, a citizen of the United States, residing at Ancon, Canal Zone, Panama, have invented 5 certain new and useful Improvements in Mechanical Photograph and Blue-Print Driers, of which the following is a specification.

This invention relates to an improved print 10 drier or oven adapted to quickly dry photographs and blue prints after the same have been washed to remove the chemicals therefrom.

It is a primary object of the invention to 15 provide a mechanical photograph and blue print drying oven employing flat heating plates designed to replace the ordinary drum as generally employed in print drying machines, the device being constructed with a 20 view to simplicity and economical production as well as economy in operating the device, especially for heat or fuel for drying purposes, all of the parts of the heating device being arranged within an oven whereby 25 to quickly absorb the moisture from the photograph or print paper and to dry the apron upon the return thereof to a position to dry other prints, which drying is accomplished quickly to facilitate rapidity in business, 30 thereby reducing the cost of upkeep.

A further object of the invention is to 35 provide an improved print drying machine or oven, which comprises a simple frame construction adapted to support the operative parts of the drying mechanism including a pair of aprons between which the photograph or print is run, the device being adapted to be rotated in any suitable manner preferably by means of a small motor 40 properly geared to the operative mechanism to cause the print to pass through the machine in from two to three minutes so as to accomplish efficient drying without the necessity of using blotters, reironing to dry 45 or prevent curling, the device being also constructed with a view to lightness of weight, particularly by avoiding the use of a large heating drum directly exposed to cooling and for this purpose, disposing the drying mechanism within an oven which forms 50 the substantial characteristics of the device, for efficiently drying the photograph or print paper and delivering the same for immediate use.

With the above and other objects in view, my invention comprises the novel features of

construction, combinations of elements and arrangement of parts which will be more fully described in the following specification and set forth with particularity in the 60 claims which are appended hereto and which form an essential part of the same.

Reference is had to the accompanying drawings forming a part of this application, wherein similar reference characters 65 will refer to corresponding parts throughout the several views, in which—

Figure 1 is a side elevation of my improved mechanical photograph and print 70 drying oven,

Fig. 2 is a vertical longitudinal sectional view of the machine,

Fig. 3 is a fragmentary enlarged vertical sectional view transversely of the device at 75 the discharge end,

Fig. 4 is an enlarged fragmentary vertical sectional view showing one of the tension members for taking up slack in an apron or to allow for stretching and shrinking of the same, and 80

Fig. 5 is a perspective view of one of said 85 apron tightening or tension members.

Referring to the drawings in detail, my improved photograph and blue print drying oven is shown as comprising a frame 10 90 including two triangularly shaped opposed side frames 11 disposed with the base portions 12 thereof on an incline, with one side 13 horizontally disposed and the other side 14 also disposed in an inclined position at a greater inclination than the base 12. The base 12 is disposed on an incline of about sixty degrees from the vertical or thirty degrees from the horizontal, while the reverse applies to the side portion 14, which 95 latter is disposed at an angle of about sixty degrees from the horizontal and about thirty degrees from the vertical. All of the frame parts are preferably constructed of angle iron, the frame being suitably connected and 100 supported upon corner legs 15 and 16 respectively disposed at the feed and discharge ends thereof as shown.

Arranged over the frame except at the ends thereof, is a casing or oven 17, the 105 same being preferably of light sheet metal and substantially rectangular in plan, so as to inclose the heating and drying elements and to protect the same from the cooling effect of external atmosphere. This casing 110 is preferably made up of two side portions 18, a top 19 which is formed integral with

the ends 20 and 21, and a bottom portion 22 all secured to the frame and also serving to rigidify the latter upon the legs 15 and 16 as previously explained.

5 The receiving portion or table of the frame is designated 23 and at this corner of the frame, there is disposed a roller 24 preferably about one and a half inches diameter, while disposed at the apex of the frame, 10 that is the meeting ends of the portions or sides 13 and 14, is a large drum or roller 25 forming the feed roller and drive roller of the device, the same being journaled through the medium of a shaft 26. Journaled in the 15 side portions of the frame adjacent to and beneath the roller or drum 25, are smaller rollers 27 and 28, while journaled in the side portions 13 of the casing is a roller 29 disposed between the rollers 24 and 27.

20 Journaled in the side portions 14 of the frame at the bottom portion of the wall 21 is a roller 30 and immediately below, at the extreme side or point of intersection of the side portion 14 with the base 12 as distinguished 25 from the location of the roller 24 at the point of intersection of the side 13 of the base 12, is a roller 31. Disposed or trained over the rollers 24, 25 and 31 is a drying belt or apron 32, the same passing 30 under the rollers 27 and 28 before passing over the roller 25 and around the same for a maximum portion of its circumference, while also passing under the rollers 29 and 30 to be driven by the roller 25 and other 35 means, as will be subsequently described. Coöoperating with the drying belt or apron 32 is a drying belt or apron 33, the same being disposed under the rollers 27 and 28 and over the roller 25 and then passing around 40 the rollers 29 and 30. The top lap of the belt is disposed over a roller 34 journaled in triangular side plates 35 above the roller 25, which plates also serve in conjunction with the apex of the frame produced by the side 45 portions 13 and 14, to rotatably support the shaft 26 of the roller 25.

The parts are designed to be driven in the directions indicated by the arrows and the upper lap of the belt or apron 32 and the 50 lower lap of the apron 33 are designed to pass over flat drying plates 36 and 37 disposed between the side portion 13 and the side portion 14 adjacent to the apex of the same and over a heating space indicated at 55 38 designed to receive therein suitable heating means such as electricity, gas or otherwise. As shown, the base portions 12 have supported therein, heating elements 39 adapted to be electrically operated at any 60 well known way as well as controlled and regulated to secure the exact desired degree of heat within the oven to more efficiently dry the prints or the like.

65 Thus, it will be seen that as heat is supplied within the oven, the plates 36 and 37

will be heated and thereby when the print paper is fed into the machine, it is placed upon the exposed lap of the apron 32 indicated at 23 and caused to pass through the slot 40 and between the aprons 32 and 33, 70 being thereby dried and discharged through the opening 41 into a receiving pan, in a thoroughly dry and flat condition. The belts take up the moisture from the photographs and prints, owing to the latter being 75 wet from washing them to remove the chemicals and as they are returned, the idle portions of the apron are dried. The aprons therefore are caused to stretch and shrink successively, and therefore it is necessary to 80 provide means for taking up the slack or allowing for the shrinkage. For this purpose, a plurality of idle rollers or tension members are provided, the same comprising rollers 43 carried upon the ends of arms 44 pivoted as shown at 45 in the respective portions 85 12, 13 and 14 of the frame, the pivots thereof being engaged by coiled springs indicated at 46, one end of each spring being anchored to the frame and the other end anchored to 90 an arm, so as to normally hold the arm outwardly against the belt or aprons, to move inwardly and outwardly for taking up slack when the belt stretches and to allow for shrinkage and always keep the aprons or 95 belts in taut condition. In this manner, the photographs or prints are positively delivered in a dry and flat condition.

In order to impart rotation to the rollers and also the aprons or belts, for moving the 100 latter in the drying operation, as previously explained, the roller 25 which is drive roller, is suitably driven. For this purpose, the frame is preferably provided with a bracket or stand 47 upon which is supported a small 105 electric motor 48, constituting an individual drive for each machine. It is essential that the parts be driven slowly so as to take about two or three minutes for the paper to pass through the machine in order to thoroughly 110 dry the same, and for this purpose the shaft of the motor is provided with a worm as shown at 49 adapted to mesh with a worm gear 50 journaled in the side of the casing or otherwise. This worm gear carries a spur 115 gear 51 meshing with a larger spur gear 52, which latter gear carries a smaller gear 53 meshing with a larger gear 54 in turn meshing with a smaller gear 55 which drives the shaft 26 from a gear 56, this constituting 120 a positive, steady and slow drive, sufficient to deliver the prints with such rapidity however, as to accommodate all needs. The receiving pan is indicated at 57.

From the foregoing description taken in 125 connection with the accompanying drawings, it is thought that a clear and comprehensive understanding of the construction, operation and advantages of my invention may be had, and while I have shown and de- 130

scribed the device as embodying a specific structure, I desire that it be understood that such changes may be made in said structure as do not depart from the spirit and scope 5 of the invention as claimed.

Having thus described my invention, what I claim as new, and desire to secure by Letters Patent, is:

1. In a mechanical drier for photographs, blue prints and the like, a frame comprising substantially triangular side portions suitably connected, supporting means therefor, a plurality of hot plates supported by the frame, a casing over the same producing an oven, and heating and drying aprons movably supported by the frame and designed to receive and deliver the photographs, blue prints and the like, heating means within the casing supported by the frame and drive 20 means for said aprons.
2. In a mechanical drier of the class described, a pair of triangular frames with one side disposed on a horizontal plane and the other side disposed on an incline, the base 25 also being disposed at an incline, said horizontal portion constituting a receiving portion, an apron mounted to move around said frame, an apron coöperating therewith and

between which the prints and the like are adapted to be moved in drying the same, 30 heating means including warming plates beneath the drying portions of the apron, rollers over which said aprons operate, means for taking up the slack and allowing for shrinking of the aprons, means for moving 35 the same, and an oven inclosing the aprons and heating means, said aprons projecting from the oven at the receiving and discharge end portions thereof.

3. The combination with a table suitably 40 supported, of rollers journaled in the table, a pair of belts disposed with one lap in contact with one lap of the other, movable over said table tension means for the laps disposed remote from each other and includ- 45 ing spring pressed rollers acting on said laps, a drive roller around which both of said laps operate, rollers adjacent to and beneath said last named roller, heating means beneath the coöperative lap, and means for 50 driving said drive roller at a relatively slow speed.

In testimony whereof, I affix my signature hereto.

CLIFTON F. SAUNDERS.
